UNITED STATES PATENT OFFICE.

GEORGE PESIKAN, OF RALPHTON, PENNSYLVANIA.

BAYONET.

1,249,476.

Specification of Letters Patent. Patented Dec. 11, 1917.

Application filed August 21, 1917. Serial No. 187,492.

To all whom it may concern:

Be it known that I, GEORGE PESIKAN, a subject of the King of Montenegro, residing at Ralphton, in the county of Somerset 5 and State of Pennsylvania, have invented certain new and useful Improvements in Bayonets, of which the following is a specification.

The primary object of this invention is to 10 provide a bayonet which may be attached in the usual manner to a rifle, and which in addition to functioning as a bayonet, is provided with means for holding a smoke-producing cartridge, whereby the bayonet, 15 or the gun to which the bayonet is attached, will constitute smoke-producing holding means, enabling the placing of the gun or bayonet attached to the gun in such position that a smoke screen will be provided, 20 behind which the soldier will be shielded, whether he be digging a trench, or retreating from a foe, as the case may be.

The invention involved herein comprises a socket or sleeve member of the usual 25 form for attaching to a rifle or the like; it also comprises a stem which carries a knife or the bayonet proper; it also comprises one or more prongs or holders through which smoke-producing cartridges are attached. All of this construction will be 30 hereinafter more specifically described and then particularly claimed, and in describing the invention in detail, reference will be had to the accompanying drawings forming 35 a part of this specification, and wherein like numerals of reference will be employed to designate like parts throughout the different views, in which:—

Figure 1 is a view in side elevation showing 40 an ordinary military rifle equipped with a bayonet constructed in accordance with my invention.

Fig. 2 is an illustrative view showing a portion of the rifle mounted in a trench 45 partially dug, the bayonet carrying a cartridge for producing the smoke screen,

Fig. 3 is a top plan view of the bayonet constructed in accordance with this invention, and

Fig. 4 is a detail view partially in elevation and partially in section, of a modified form of bayonet, the prongs being broken away.

In the drawings 5 represents a rifle to 55 which the bayonet is adapted to be attached.

The bayonet comprises a socket, sleeve, or attaching member 6 of the usual bayonet lock type for affixing to the end of the barrel of the gun 5. This socket carries a somewhat S-shaped arm 7 at its extremity which 60 is bent outwardly and extended to form a stem 8 that terminates in the bayonet knife 9.

Carried by the stem 8 near its inner end is a plurality of pointed prongs 10. Generally, three of these will be sufficient, and 65 this is the number shown in the preferred form of construction. However, this may be constructed as shown in Fig. 4 in which 8' indicates the stem, and 9' the prongs. In this construction four prongs are provided, 70 each pair of prongs being formed from a single piece of material which is passed through an opening in the stem.

11 indicates a smoke-producing cartridge. In practice, I have formed this cartridge of 75 waste material, tar, and oil; obviously it may be formed of any material capable of producing great volume of smoke when ignited, and I do not wish to limit myself in any manner to the material of which such 80 cartridge is constructed.

When it is desired to dig a trench, it will be obvious that the soldier may lay his gun with the bayonet of this construction in front of the place where the trench is to be 85 dug, ignite one or more cartridges, and thus produce a screen of smoke to shield him while working on the trench. Obviously, if he is interrupted in the trench digging, the gun with bayonet attached is ready for 90 instant use. Further, in making a charge with the gun equipped with a bayonet of this type, should it be necessary for the soldier to retreat, it is only necessary to 95 ignite one or more of the smoke-producing cartridges, to give him a screen of smoke which will shield him during such retreat. The prongs being well back of the bayonet, the effectiveness of the latter is in no wise decreased when it is necessary to use the 100 same.

Should it be desired, the bayonet can be mounted on a short stick or post instead of on the gun, and the same stood on the ground in front of the point where it is 105 desired to dig a trench.

While the constructions herein shown and described embody the principle of the invention, it is to be understood that the same may be changed and modified within the 110

scope of the invention as claimed without departing from the spirit of the invention.

What I claim is:—

1. A bayonet comprising an attaching member, an offset stem projecting therefrom and formed at its outer end into a knife, and prongs carried by said stem.
2. A bayonet comprising an attaching member, a laterally positioned knife, and laterally positioned cartridge carrying prongs.
3. A bayonet comprising an attaching member, a knife laterally offset therefrom and lying in a plane parallel with the axis

of the attaching member and a cartridge 15 carrying prong projecting from the shank of the knife and laterally spaced relative to the attaching member.

4. A bayonet comprising an attaching member, an S-shaped extension projecting laterally therefrom and terminating in a stem extending parallel with the axis of the attaching member, said stem carrying a knife, and a cartridge carrying prong carried by said stem.

In testimony whereof I affix my signature.

GEORGE PESIKAN.
